CLAIM

The ornamental design for a high performance cooling device, as shown and described.

DESCRIPTION

FIG. 1 is a top front left perspective view of a first embodiment of a high performance cooling device showing my new design;

FIG. 2 is a front elevation view thereof;

FIG. 3 is a right elevation view thereof;

FIG. 4 is a bottom view thereof;

FIG. 5 is a top plan view thereof;

FIG. 6 is a top front left perspective view of a second embodiment of a high performance cooling device showing my new design;

FIG. 7 is a front elevation view thereof;

FIG. 8 is a right elevation view thereof;

FIG. 9 is a bottom view thereof; and,

FIG. 10 is a top plan view thereof.
